UNITED STATES PATENT OFFICE.

AMOS J. SCRITCHFIELD, OF EUGENE, OREGON, ASSIGNEE OF ONE-HALF TO IRA F. REBBEN, OF BOISE, IDAHO.

ENVELOPE FASTENER.

Application filed April 29, 1925, Serial No. 26,733. Renewed August 3, 1926.

The present invention relates to an envelope fastener and has for its prime object to provide a device of this nature having a very simple and efficient construction, one which is reliable, inexpensive to manufacture, strong, easy to manipulate, and well adapted to the purpose for which it is designed.

With the above and other objects in view as will appear as the description progresses, the invention resides in certain novel features of construction, and in the combination and arrangement of parts as will be herein-after more fully described and claimed.

15 In the drawing:

Figure 1 is an elevation of an envelope with the fastener attached thereto,

Figure 2 is a section taken on the line 2—2 of Figure 1,

20 Figure 3 is a perspective view of the fastener showing the same on a portion of an envelope, the fastener being in its open position,

Figure 4 is a detail section taken substantially on the line 4—4 of Figure 3, and

25 Figure 5 is a detail perspective of a portion of the fastener.

Referring to the drawing in detail it will be seen that 1 designates an envelope provided with the usual flap 2 which is to be fastened to the back 3.

30 My device consists of a U-shaped body portion 4 which is adapted to be engaged over the back 3 of the envelope so that one leg 5 extends on the inner side thereof and the other leg 6 on the outer side thereof. An extension 7 is provided on the lower edge of the leg 6 and is bendable to the position shown in Figures 1 and 3 and the flap 2 is to be held between the leg 6 and the extension 7 when said extension is bent in parallelism to said leg 6 with the flap therebetween as is illustrated to advantage in Figure 2. The two legs 5 and 6 and the extension are provided with registerable openings or slots 8. Openings 9, preferably four in number, are provided in each leg of the body 4 and are registered with one another. A housing 10 is formed with front and rear plates 11 and 12 respectively connected by edge plates 13. The rear plate 12 is provided with a slot 14 adapted to be registered with slots 18 in the legs 5 and 6 of the body 4. A plurality of prongs 15 are struck from the plate 12 so as

to penetrate openings 9 of the legs 5 and 6 and the portion of the back 3 of the envelope disposed therebetween and these prongs are then bent over the leg 6 after holding the body assembled on the back of the envelope with the housing 10 inside of the envelope. 55 A fastener 17 constructed with the two arms 18 which slightly diverge normally at their terminals is adapted to be passed through the slots 8 and 14 when the envelope is to be sealed. The diverging terminals of the arms 18 of the fastener 17 will engage the front plate 11 of the housing 10 causing them to spread further apart as is shown in Figure 2 and assume a locked position for holding the slot 2 of the envelope firmly between the extension 7 and the leg 6. 60

It is thought that the construction and advantages of the invention will now be clearly understood without any more detailed detailed description thereof. It is desired, 75 however, to point out that the changes in the details of construction, and in the combination and arrangement of parts may be resorted to without departing from the spirit or scope of the invention as hereinafter 80 claimed or sacrificing any of its advantages.

Having thus described my invention, what I claim as new is:

1. An envelope fastener of the class described including a U-shaped body, a housing fixed to one leg of the body, an extension fixed to the other leg of the body and bendable to extend parallel therewith or at angles thereto, said body, housing, and extension provided with registerable openings, and a 85 fastening element insertable through said openings all in the manner and for the purpose specified.

2. In combination with an envelope, a fastening device including a U-shaped body 95 straddling the upper edge of the back of the envelope and provided on one leg with an extension, a housing fixed to the other leg within the envelope, said body, said extension and said housing provided with registerable openings and a fastening element provided with a pair of legs insertable through the openings and having slightly diverging terminals to engage the housing and to be spread when forced into engagement therewith. 100

3. In combination, an envelope, a fastening device associated with the envelope and

including a U-shaped body to form a pair of legs straddling the upper edge of the back of the envelope so that one leg is situated interiorly thereof and the other exteriorly thereof, an extension formed on the lower end of the exterior leg and bendable to receive the flap of the envelope between the exterior leg and the extension, said legs and said extension provided with registerable slots, a housing including a thumb plate, a rear plate, and two end plates, said rear plate provided with prongs adapted to pierce the legs of the body, and the rear of the envelope and to be bent so as to hold said body and said housing in place, the rear plate of said housing being provided with a slot registerable with the other slots, and a fastening

element provided with a pair of legs having diverging terminals, said legs being insertable through the slots and engageable with the front wall of the housing so that they may be spread into locking position.

4. A device of the character described including a U-shaped body, a housing secured to one leg of the body, means for securing the said housing and body upon an envelope, a bendable extension formed at the outer side of the body, and means for engaging a detachable fastening element with the said bendable extension and body for fastening the envelope.

In testimony whereof I affix my signature.

AMOS J. SCRITCHFIELD.
